Specification of Letters Patent. Patented Oct. 10, 1916.

Application filed December 13, 1915. Serial No. 66,475.

To all whom it may concern:

Be it known that I, OSCAR ROESEN, a citizen of the United States, residing at New York city, county of Kings, and State 5 of New York, have invented certain new and useful Improvements in Printing-Machines, fully described and represented in the following specification and the accompanying drawings, forming a part of the 10 same.

This invention relates to certain improvements in printing cylinders of that class in which the cylinder is a printing plate cast or otherwise produced in a tubular or cylindrical form. This form of printing cylinder has certain well-known advantages in the printing art. To employ a printing cylinder in the form of a tubular plate, however, because of its shape, special forms of 15 press construction must be employed, in order to support the plate in printing position in the machine, so that it can be removed and placed in position in the machine.

It is the object of the present invention to 20 produce an improved construction whereby such tubular plate may be so supported in printing position in the machine as to be readily and easily removed and placed in position, and in which the parts employed 25 for supporting the plate are simple and easily accessible.

With these and other objects in view, the invention consists in certain novel combinations and parts which will be hereinafter 30 fully described.

For a full understanding of the invention 35 a description of the same will be given in connection with the accompanying drawings, in which—

Figure 1 is a vertical section, partly broken away, of two tubular printing plates with the supporting means in engagement with the plates for supporting them in printing position; Fig. 2 is a similar view 40 showing the plate freed from the supporting means and ready to be removed from the machine; Fig. 3 is a diagrammatic end elevation, partly in section, of one arrangement of the printing couples in a printing 45 machine employing the improved construction for supporting tubular plates; Fig. 4 is a front view, partly in section, of one of the form members of the printing couples shown in Fig. 3; Fig. 5 is a vertical cross 50 section taken on the line 5—5 of Fig. 1;

Fig. 6 is a vertical section, partly broken away, of a modified form of support for the plates, showing the supporting means in engagement with the plates; Fig. 7 is a similar view showing the plate ready to be removed from the machine; Fig. 8 is a diagrammatic end elevation, partly in section, of a different arrangement of the printing couples from that shown in Fig. 3; Fig. 9 is a plan view, partly in section, of one of the printing couples shown in Fig. 8, and Fig. 10 is an end view, partly in section, taken on line 10—10, Fig. 6.

Referring now to the drawings, the invention has been illustrated as embodied in 70 a rotary web perfecting printing machine, though the invention is adapted for use and may be used in other types of printing machines. In such machines, as shown, usually a plurality of tubular plates are employed 75 in each printing couple, the plates being arranged end to end, but it will be understood that if desired one such tubular plate may be employed, and that the invention is not to be limited to the use of any particular 80 number of plates. In the machine illustrated, referring first to Figs. 1 to 5, four such plates, which, furthermore are preferably completely circular, are employed with each couple, these plates being arranged end 85 to end. The arrangement of the couples in the machine may also be varied as desired.

In the particular construction illustrated in Figs. 1 to 5, which show a rotary perfecting press, there are provided a pair of printing couples arranged in line, the cylinders of the couples being in the same horizontal plane and each including form cylinders 1 and 2 and impression cylinders 3 and 4, the form cylinders being inked in the usual 90 manner from distributors 5 taking ink from fountains 6, through the usual train of distributing rolls 7. Each form member includes in the particular construction illustrated four tubular cast plates 8 which may be dimensioned as desired, either one page around, or two pages around, the plates being cast in molds suitably constructed to produce a completely circular plate. These plates form the printing cylinders and are supported, preferably and for the sake of simplicity in construction and ease in removing plates from the machine and in positioning them in the machine, only at their ends, 95 so that when freed from the supporting 100

105

110

- means the plates may be readily removed from between such means and may be quickly placed in position therebetween and clamped in position. The particular means for thus supporting the plates may be somewhat varied, but these supporting means will include a pair of heads 9, 10 for each plate, these heads being mounted so as to have rotary engagement with the plates at the ends thereof, so that by moving one of the heads away from the other the plates may be freed and removed sidewise from between the heads. The particular construction for effecting this may be varied, but in the preferred construction and as shown in Figs. 1 and 2, in which two plates are shown positioned end to end, one of the heads, as 9, will, while having a rotary movement, be fixed against lateral movement with respect to the plate, while the other heads are mounted so that they may have a lateral movement relatively to the stationary heads. The stationary heads are mounted so as to rotate with the plate in any suitable manner. In the particular construction illustrated, there is provided a supporting frame 11 suitably secured to the main frame of the machine, this frame forming a bearing for one of the heads which is provided with a hollow projecting sleeve 12 rotating in this bearing frame. The other fixed head 9 is provided with a projecting stud or stem 30, which enters the hollow sleeve 12 of the other head 9, and is suitably secured thereto by a key and slot construction 31, the two heads 9 thus rotating together. The movable heads 10 and the means for moving them are identical in construction, and only one will be described. This head is mounted so as to have a rotary movement and at the same time a lateral movement relatively to the other head, so that it can be freed from the plate. While the particular means for thus mounting the movable head may be varied, in the particular construction illustrated in Figs. 1 and 2 this head is carried on a shaft 13 which takes bearing in sliding sleeve 14, the shaft being rotated in any suitable manner, as by sliding gear 15. The sleeve 14 is supported in a main frame 18 and is given a sliding movement to move the head. The lateral movement of the sleeve 14 may be effected in any suitable manner. In the particular construction illustrated, the sleeve has secured thereon a rack 19, this rack being moved laterally by means of a pinion 20 on a shaft 21 which is or may be rotated by the use of a wrench or other suitable tool.
- In constructions embodying the invention in its preferred form, locking means are provided between the heads and the plate, so that the heads positively engage the plate and any slipping between the plate and heads during the rotation of the parts is effectually prevented. While these locking means may be of various character, in the particular construction illustrated the plate is cast with a plurality of grooves 22 near the ends thereof, into which take lugs 23 formed on the heads, this construction being adopted for both the heads 9 and 10. In the best constructions, furthermore, means are provided whereby the plate is accurately positioned in the heads. While these means may be varied, as shown they include stops 25 formed on the plate at each of its ends between the groove 22 before referred to, against which take flanges 26 on the heads.
- With the construction so far described, the plates are freed at one end by the withdrawal of the movable head. In machines embodying the invention in its preferred form, means will be provided for positively freeing the ends of the plates from the stationary heads. In machines embodying the invention in its best form, furthermore, these means will be operated through suitable connections from the head-moving means, the connections being such that the movable head is first withdrawn from one end of the plate and then the plate is removed from the stationary head at its other end. While these means may be varied, in the particular construction illustrated there are provided a number of pusher rods 27, one for each of the plates. These rods and operating connections are identical in construction and only one of them will be described. Referring to Figs. 1 and 2, as illustrated these rods take bearings in the frames 11, 18, before referred to, being slidably mounted in these frames. Each of the rods carries a suitable pushing member for pushing the plate off the head. The construction of this member may, of course, be varied, but as shown it is a pusher block 28 fast on the rods and having a pushing face 29 arranged to contact with the edge of the plate. This pusher block and rod is operated in any suitable or desired manner, but as before stated, in the preferred construction it will be operated to remove the plate after the head 10 has been withdrawn therefrom. While the particular means for effecting this may, of course, be varied, as illustrated the sliding sleeve 14, before referred to, is provided at one end with a hanger arm 32 which is in sliding engagement with the bar 27. Beyond the hanger arm on the bar is located a stop collar 33, against which the hanger arm 32 takes. During the first portion of the movement of the rack by which the head 10 is removed from the plate, the hanger arm slides idly on the rod. The continuing movement of the rack causes the hanger arm to take against the stop collar 33 and to move the rod 27 and, through it, the pusher block 28, thus freeing the plate from the fixed head 9.

If desired, to insure the head 10 remaining clear of the plate when the plate is removed from the fixed head 9 by the pusher bar, as before described, a suitable stop, as a 5 stop pin 34, mounted in the frame of the machine, may be provided, this pin taking against the edge of the plate when the plate is in the position shown in Fig. 2, this pin preventing the plate from coming into engagement with the movable head 10.

In Figs. 6 to 10, inclusive, is shown a modification of the construction which may be employed, if desired, particularly where there are to be but two plates arranged end 15 to end, or a single plate. Certain parts of the construction shown in these figures are identical with those heretofore described in reference to Figs. 1 to 5, inclusive, and need not again be described in detail, the 20 same reference numerals having been used to indicate similar parts. In the construction shown, however, in these figures, the fixed heads 9, between two adjacent plates, are rotatably mounted by means of a 25 slightly modified construction. As illustrated, referring to Figs. 6 and 7, there is provided a support, as an arm 11', suitably secured to the main frame of the machine, this arm carrying studs 12' projecting from 30 each side thereof, on which studs the heads 9 rotate. If desired, and as shown in Figs. 6 and 7, the pusher heretofore described for removing the plate from the stationary head may be omitted, the plate being simply 35 pushed off by hand after the movable head has been withdrawn.

If desired, and as shown in Figs. 6 and 7, a positioning device may be employed for positioning the movable head 10 with respect 40 to the plate. While this device may be varied, in the preferred construction and as shown there is provided a bearing 17 suitably mounted in the frame, the bearing 17 having a spring-seated pin stop 16 mounted 45 therein and taking into an opening in the sleeve 14, this stop being withdrawn from the sleeve when the head is moved laterally to free the plate.

In Fig. 8 is illustrated another arrangement of the printing couples, which may be employed, if desired. In the construction here shown, the couples are arranged with the form members 1', 2' arranged below form members 3', 4' and opposing each 55 other, this arrangement being particularly adapted for certain press purposes. The form cylinders in this arrangement are inked in the usual manner through distributors 5' taking ink from fountain 6' 60 through the usual train of distributing rolls 7'.

Machines embodying the invention will include a support for receiving the plate after it has been freed from the head. While 65 this support may vary somewhat in char-

acter, in the particular construction shown this support will consist of a curved frame 35 which may extend the length of the plates, as shown in Figs. 6 and 7, this frame being suitably secured to the main side 70 frame of the machine, this frame being located closely adjacent the plate, the plate dropping onto this frame when it has been released from the heads. If desired, this support may consist of a number, as for 75 instance, a pair, of short curved supports 36 carried by the rods 27, before referred to. As shown in Figs. 1 and 2, these short curved supports are located at or near each end of the plate and closely adjacent thereto, the plate dropping onto these supports after it has been freed from the heads.

While the construction so far described has been with reference to two plates arranged end to end, the use of more than 80 two plates arranged end to end is contemplated by the present invention, and one such arrangement, in which more than two plates arranged end to end is used is shown in the drawings. Referring to Fig. 4, there 85 is illustrated an arrangement in which there are four plates arranged end to end. In this construction, as in the construction previously described, there are provided a pair of heads for each of the plates. These 90 heads, when this arrangement is used, may be mounted in either of the ways heretofore described, they being mounted in the particular construction shown, in the manner described in reference to the construction 95 shown in Figs. 1 to 5. Where, as in the arrangement shown, there are four plates arranged end to end, means will be provided whereby the middle plates may be removed from between the heads in order 100 to take them from the machine, or to re-position them therein. While these means may vary somewhat in character, in the particular construction illustrated means will be provided whereby the heads between the 105 inner ends of two outside plates and the plates adjacent thereto may be given a bodily movement sidewise. In the particular construction illustrated, there is provided a bearing frame 37, which may be stationary, located between the two inside plates 38, 39, and two movable bearing frames 40, 41 located between the outside plates 42, 43 and the plates adjacent thereto. These bearing frames 37, 40, 41 carry 110 supporting heads, and the outer ends of the outside plates 42, 43 engage and are supported by laterally movable heads 44, 45 which are removed from the plates in the same manner as before described. The laterally movable bearing frames 40, 41 may 115 be moved in any suitable manner, as through a screw construction 46 on rods 47, operated in any suitable manner, as by a hand tool. In removing plates in this construction, the 120

125

movable heads 44, 45 are first moved laterally, freeing the outside ends of the two outer plates, which are then removed from the heads engaging them on bearing frames 40, 41, as by pushing the plates off therefrom. The bearing frames 40, 41 are then moved laterally away from bearing 37. In this way the inner plates may be freed from their supporting heads on the frames 40, 41, the heads on the movable frames being withdrawn from the plates and the plates pushed off the heads on frame 37.

With the construction described, a very simple and efficient means is provided for securing the tubular plates in the machines, all unnecessary shafting for supporting the plates having been eliminated, and the mechanism for freeing the plates being exceedingly simple and easy to get at.

20 It is understood that while the invention has been shown in its preferred form, various changes may be made in the specific construction for effecting the results obtained without departing from the invention.

25 What is claimed is:

1. In a printing machine, the combination with tubular printing plates arranged end to end, of a pair of heads engaging with adjacent ends of the plates, a pair of heads engaging with the other ends of the plates, and means for withdrawing one of the pairs of heads from the plates to free them and permit the plates to be removed from the other heads.

2. In a printing machine, the combination with tubular printing plates arranged end to end, of a pair of heads engaging with adjacent ends of the plates and fixed relatively thereto, a pair of movable heads engaging with the other ends of the plates, and means for withdrawing the movable heads from engagement with the plates to free them and permit the plates to be removed from the other heads.

3. The combination with a plurality of tubular plates arranged end to end, of a pair of heads engaging the outer ends of the outer plates and movable laterally relatively to the plates, a pair of heads engaging the inner ends of the outer plates and the outer ends of the plates adjacent thereto and movable laterally, a pair of heads engaging with the inner ends of the inner plates, and means for moving the heads at the outer ends of the outer plates.

4. The combination with a plurality of tubular plates arranged end to end, of a pair of heads engaging the outer ends of the outer plates and movable laterally relatively to the plates, a pair of heads engaging the inner ends of the outer plates and the outer ends of the plates adjacent thereto, laterally movable bearings for these heads, a pair of heads engaging with the inner ends of the

inner plates, means for moving the heads at the outer ends of the outer plates, and means for moving the bearings laterally.

5. The combination with a pair of tubular plates arranged end to end, of heads in engagement with the adjacent ends of the plates and rotatably connected together, a pair of movable heads engaging with the outer ends of said plates, and means for withdrawing the movable heads from the plates.

6. The combination with a pair of tubular plates arranged end to end, of heads in engagement with adjacent ends of the plates, a pair of movable heads engaging with the outer ends of said plates, means for withdrawing the movable heads from the plates, and connections for pushing the plates from the other heads.

7. In a printing machine, the combination of a tubular printing plate, a pair of heads engaging with the plate and holding it in printing position, means for withdrawing one of the heads from engagement with the plate to free it from the plate, and connections for pushing the plate from the other head.

8. In a printing machine, the combination of a tubular printing plate, a pair of heads engaging with the plate and holding it in printing position, means for withdrawing one of the heads from engagement with the plate to free it from the plate, and connections from the head-moving means for pushing the plate from the other head.

9. In a printing machine, the combination of a tubular printing plate, a pair of heads engaging with the plate and holding it in printing position, means for moving one of the heads to free it from the plate, and connections operating after the head is freed for pushing the plate from the other head.

10. In a printing machine, the combination with a tubular plate, of a pair of heads between which the plate is clamped, a rack and pinion for moving one of the heads, a pusher, a pusher rod, and connections between the rack and pinion and the pusher rod whereby the movement of the rack first frees the movable head from the plate and then causes the pusher to operate to free the plate from the other head.

11. In a printing machine, the combination of a tubular printing plate, a pair of heads engaging with the plate and holding it in printing position, means for withdrawing one of the heads from engagement with the plate to free it from the plate, connections for pushing the plate from the other head, and a support for receiving the plate after it is freed from the heads.

12. In a printing machine, the combination of a tubular printing plate, a pair of heads engaging with the plate and holding it in printing position, means for withdrawing

70

one of the heads from engagement with the plate to free it, and a support beneath the plate for receiving the plate when it has been freed from the heads.

5 13. In a printing machine, the combination of a tubular printing plate, a pair of rotating heads, coöperating holding means between the heads and plate for preventing a slip between the heads and plate when 10 they are rotating, means for withdrawing one of the heads from engagement with the plate to free it, and a support for receiving the plate when it has been freed from the head.

14. In a printing machine, the combination, 15 with a plurality of tubular plates arranged end to end, of a pair of heads for supporting each plate in printing position, the heads at the outer ends of the outer plates being movable relatively to the plate, 20 means for moving the movable heads to free them from the plates, and a support for receiving the plate after it is freed from the head.

In testimony whereof, I have hereunto set 25 my hand.

OSCAR ROESEN.
